United States Patent Office

Des. 190,762
Patented June 27, 1961

190,762

DOWEL UNIT FOR LUGGAGE OR THE LIKE

Charles S. Gehrie, Montclair, N.J., assignor to Presto
Lock Co., Garfield, N.J., a limited partnership

Filed Jan. 10, 1958, Ser. No. 49,186

Term of patent 14 years

(Cl. D50—7)

Fig. 1

Fig. 3

FIG. 1 is a front elevational view of a dowel unit for luggage or the like embodying my new design;

FIG. 2 is a side elevational view thereof; and

FIG. 3 is a top plan view thereof.

I claim:

The ornamental design for a dowel unit for luggage or the like, as shown.
